(57) **CLAIM**

I claim the ornamental design for the braiding device, as shown and described.

DESCRIPTION

FIG. 1 is a top view of the preferred embodiment of the braiding device of this invention. The bottom view is identical to the top view.

As shown in FIG. 1, the braiding device includes two cavities with an arcuate element extending into each cavity.

FIG. 2 is a front elevational view of the preferred embodiment of the braiding device of this invention. The rear elevational view is a mirror image of the front; and,

FIG. 3 is a left side elevational view of the preferred embodiment of the braiding device of this invention. The right side elevational view is a mirror image of the left side.
